UNITED STATES PATENT OFFICE.

MUNN DAVIS, OF WAHOO, NEBRASKA.

END-GATE FOR WAGONS.

SPECIFICATION forming part of Letters Patent No. 363,609, dated May 24, 1887.

Application filed November 23, 1886. Serial No. 219,688. (No model.)

To all whom it may concern:

Be it known that I, MUNN DAVIS, of Wahoo, in the county of Saunders and State of Nebraska, have invented a new and useful Improvement in End-Gates, of which the following is a full, clear, and exact description.

My invention relates to an improvement in end-gates for wagons or any dumping apparatus—such as carts, dump-cars for coal or ore, steam shovels, excavators, and dredgers—and has for its object to dump the load by a single movement, and while the apparatus to which it may be attached is in any given position. The object is also to provide a device which will occupy little space and be permanently attached to the end-gate, whereby the said device will be always at hand when needed.

The invention consists in the construction and combination of the several parts, as will be hereinafter fully set forth, and pointed out in the claim.

Reference is to be had to the accompanying drawings, forming a part of this specification, in which similar letters of reference indicate corresponding parts in all the figures.

Figure 1 is a perspective view of my end-gate in a locked position, and Fig. 2 a partial longitudinal section through said end-gate and locking device. Fig. 3 is a central vertical section through Fig. 1 when the gate is opened, and Fig. 4 is a plan view of the guide-plate.

A represents the side-boards of a wagon, provided with cleats *a*, attached to the inner face thereof, to form grooves *a'*, in which the upper section, B, of the gate is entered, the said upper section being usually fitted with a central vertical brace, B', through an aperture in which and corresponding apertures in the side-boards A. A pin, *b*, is passed, to assist in holding the said gate in position and constitute an additional brace therefor.

A lower section, C, of a width equal to the height of the opening required and of a length equal to the distance between the side-boards

A, is hinged to the upper fixed sections, B, by apertured straps *c c'*, attached to the said sections near their outer edges in such manner as that the lower apertured end of one and the upper apertured end of the other will register in the same horizontal plane, the hinged connection being effected by passing a rod, D, through

the said apertured ends of the straps, and also through apertures in the same plane therewith formed in the side-boards A.

The straps *c'* are made to extend the entire width of the lower or hinged section, C, and are provided near their lower ends at equidistance from the bottom with an embossed or struck-up portion, *d*, forming thereby in their under face a recess, *d'*.

I attach by screwing or otherwise to the hinged section C, about centrally the same at the bottom, a thin metal plate, E, having formed therein a central aperture, *e*, and horizontal slots *e' e'*, upon each side of said aperture *e*, extending through the edges of the plate, as shown in Fig. 4. Horizontal lock-bars F, of a length about equal to half the entire width of the wagon, provided at one end with integral right-angular projections F', are passed through the recesses *d'* in the straps *c'*, and their outer straight edges enter thimbles D', secured in the side-boards A, to project usually flush with the outer face of said side-board, while the angular ends are made to enter, respectively, the horizontal slots *e' e'* in the guide-plate E.

To operate the lock-bars F, I provide another and thicker plate, H, having a central aperture and cam-slots *h h'* upon each side of said aperture, and pivot said plate H upon the guide-plate E by a bolt, H', made to pass through the central apertures of each plate and the hinged gate C, having first, however, entered the projecting ends F' of the lock-bars through the cam-slots *h h'*, where they and the pivot-pin are capped with a suitable nut and washer.

A handle, K, is provided the locking plate H at the upper portion thereof, which may be made integral therewith or attached thereto, the said handle, when the gate is locked, being adapted to engage a spring, K', secured at one end to the gate, purposed to retain the handle in a vertical position.

When it is desired to dump a load, the handle K is simply pulled to the right or left, which action causes the plate H, through the medium of its cam-slots, to withdraw the lock-bars F from engagement with the thimbles D', and as the gate is hinged near its extreme upper edge, the pressure of the load being from

the inside, the gate thereupon flies open and the load is quickly and handily unloaded.

The manner in which I hang the gate permits of any desired size of opening, and the 5 unlocking device, being attached to the gate, is always at hand when needed; again, the device is so simple that nothing is liable to disorder, and by simply withdrawing the pins the entire gate may be taken out.

10 My end-gate is equally applicable to all manner of dumping apparatus.

Having thus described my invention, what I claim as new, and desire to secure by Letters Patent, is—

15 The combination, in an end-gate, with the upper fixed section, of the lower outwardly-swinging section, the straps $c' c'$, secured to the

adjacent edges of the two sections with their eyes in horizontal alignment, the lower straps being bent outwardly to form horizontally-aligned loops d , the rod D, passed through the sides of the wagon and the strap-eyes, the plate E, secured to the center of the lower section and formed with two horizontal slots, $e' e^2$, in alignment with the loops d , the locking-plate H, centrally pivoted to the plate E and having eccentric slots $h h'$, and the locking-bars sliding in the slots $l l'$ and through the loops d , and bent outward at their inner ends and entering the slots $h h'$, substantially as set forth.

20 MUNN DAVIS.
